United States Patent Office.

FRANCIS Y. ARNOLD, OF PHILADELPHIA, PENNSYLVANIA.

Letters Patent No. 106,105, dated August 9, 1870.

IMPROVEMENT IN NON-CONDUCTING CASING FOR BOILERS, STEAM-PIPES, &c.

The Schedule referred to in these Letters Patent and making part of the same.

To all whom it may concern:

Be it known that I, FRANCIS Y. ARNOLD, of Philadelphia, in the county of Philadelphia and State of Pennsylvania, have invented a new and useful Improvement in Non-conducting Casing; and I do hereby declare that the following is a full, clear, and exact description thereof, which will enable others skilled in the art to make and use the same, reference being had to the accompanying drawing forming part of this specification.

This invention relates to a new and useful improvement in means for preventing loss of heat in steam-pipes, steam-boilers, and furnaces and pipes for heating and conveying air, gases, or water; and

It consists in the construction and arrangement of parts as hereinafter described.

In the drawing—

Figure 1 represents an end view of the casing, showing the ribs or stays.

Figure 2 is a longitudinal section of the same.

Similar letters of reference indicate corresponding parts.

A is the outer casing, which contains the non-conducting material. This casing is made of metal, in two parts, which lap by each other, as seen in the drawing, confined together by the clasp-hooks B.

C represents longitudinal ribs (more or less in number) which are connected with the outer casing A by means of the rivets D.

E represents half circles of band or hoop-iron, which are also connected with the casing and the ribs by the rivets D.

The rivets pass through both the ribs and the circles, and their ends are riveted on the outside of the casing, while their heads F project inward, and come in contact with the pipe or surface to be protected, as

seen in the drawing, where the pipe is indicated in dotted outline.

The heads of the rivets secure an empty space around the pipe or surface to be protected, which space adds materially to the effect of any non-conducting medium, as dead air is known to be one of the best of non-conductors.

G represents longitudinal strips of rubber, which are placed within the casing so as to be surrounded by the non-conducting material in the joints, to allow of expansion and contraction, and secure a tight joint for the confinement of the air.

The non-conducting casing—taken as a whole—constructed in this manner, when applied to steam, water, or hot-air pipes, may be applied in halves, and may be removed at pleasure, for making repairs or other purposes.

H represents pieces of rubber around the rivets, in contact with the outer casing, to allow of the expansion and contraction of the sheet-iron of which it is composed.

Having thus described my invention,

I claim as new and desire to secure by Letters Patent—

1. In combination with a non-conducting casing, the pieces of rubber G and H, to allow for the expansion and contraction of the casing and non-conducting material, substantially as described.

2. The outer casing A, formed in parts connected together by hooks B, the rivets D, provided with heads F on their inner ends, the ribs C, and half circles E, all arranged as shown and described.

FRANCIS Y. ARNOLD.
